UNITED STATES PATENT OFFICE.

FRANKLIN N. CONANT, OF NEWBURYPORT, MASSACHUSETTS, ASSIGNOR, BY MESNE ASSIGNMENTS, TO THE CHASE-SHAWMUT COMPANY, A CORPORATION OF MASSACHUSETTS.

RENEWABLE FUSE.

1,392,917.

Specification of Letters Patent. Patented Oct. 11, 1921.

Application filed November 22, 1917. Serial No. 203,325.

To all whom it may concern:

Be it known that I, FRANKLIN N. CONANT, a citizen of the United States, and a resident of Newburyport, county of Essex, and State 5 of Massachusetts, have invented an Improvement in Renewable Fuses, of which the following is a specification.

This invention consists of a renewable inclosed fuse of the cartridge type.

10 Figure 1 represents a longitudinal section of my fuse taken axially.

Fig. 2 represents a cross-section on the line 2—2 of Fig. 1.

15 Fig. 3 is a section of a fuse end with the component parts in separated relation.

Fig. 4 is a perspective drawing of the ferrule.

Fig. 5 is a perspective drawing of the contact plate.

20 Fig. 6 is a perspective drawing of the end cap.

Fig. 7 shows a modified form of ferrule.

As here shown, 1 represents the usual cartridge tube; 2 a ferrule, embracing the 25 end thereof and secured to the cartridge tube by pins 3, in a usual way. This ferrule is of metal, and is threaded to receive the end cap 11, hereinafter described. The ferrule is preferably flanged to embrace the 30 end of the fuse case, and has an extension 4 or 4^a across the end of the ferrule to form a bearing for the fuse link. Any suitable fuse link may be used having a flat strip terminal, the fuse link 5 here shown being 35 a flat strip, preferably zinc, having one hole in the center. Ends 6 of this fuse link are folded down over the extension 4 or 4^a of the ferrule. A plate 7, having a flat portion 8 and a wedge shaped extension 9, arranged 40 to enter the opening 10 in the end of the ferrule is then placed in position. The end cap 11 is then screwed to the threaded portion of the ferrule and drives the wedge portion 9 into the opening in the ferrule, 45 and jams the plate 7 against the terminal of the link. The wedge shaped extension 9 prevents the rotation of the plate when the end cap is screwed into place, which might injure the delicate link, and holds the link 50 against the edge of the extension 4 on the ferrule, thus giving the maximum contact. A wedge shaped protuberance is most satisfactory, but obviously any protuberance 55 which will prevent rotation of the plate and hold the link in its proper position will an-

swer the purpose. This structure has no delicate parts other than the link, and is readily placed in position without screw driver or other tools, and the contact portions are readily accessible to insure cleaning and a perfect contact.

If desired, a finely divided non-conducting material may be placed within the tube to improve the action of the fuse on short circuit.

The device without the fusible link is a 65 complete article of manufacture in itself and may be sold to be filled with any suitable link.

I claim:

1. In an inclosed electric fuse of the cartridge type, the combination of a casing containing a fuse strip, an externally screw-threaded metal ferrule for the end of said casing having an end wall formed with an 70 aperture having a straight side, wedging means to engage the fuse strip on the straight side of said aperture throughout its width, and means to engage a terminal portion of the fuse strip on the end wall adjoining said straight side, both said engaging means being removable, and an end cap arranged to apply pressure to both of 75 said engaging means to firmly hold the terminal portion of the fuse strip.

2. The combination in an inclosed electric fuse of the cartridge type of a casing, an exteriorly screw-threaded metal ferrule for the end of the same, having a permanent link supporting portion extended transversely of the end of the fuse casing, provided with an aperture, a flat fuse link, arranged longitudinally within the fuse casing and having its terminal portion bent over the edge of the aperture and over the 95 link supporting portion of said ferrule, a removable metal contact plate having a flat portion and a wedge portion, the wedge portion entering said aperture and pressing the link sidewise against the edge thereof, and the flat portion co-operating with the link supporting portion to hold the link between them, and a threaded end cap screwed upon the ferrule which presses the contact plate against the fuse link.

3. The combination, in an inclosed electric fuse of the cartridge type of a casing, an exteriorly screw-threaded metal ferrule for the end of the same having a permanent link supporting portion extended transversely of 100 105 110

the end of the fuse casing and having an aperture providing abundant space for the removal of the products of combustion and the insertion of a fuse link, a flat fuse link 5 arranged longitudinally within the casing and having its terminal portion extended through the aperture and bent over the link supporting portion of said ferrule, a removable metal contact plate having a flat portion 10 and a wedge portion, the wedge portion being fitted to enter the aperture in the end of the ferrule and press the fuse link sidewise against the edge thereof, and the flat portion being arranged to press said link against the link supporting portion of 15 the ferrule, and a threaded end cap screwed upon the ferrule for applying pressure to said contact plate.

4. The combination, in an inclosed electric 20 fuse of the cartridge type of a casing, a metal ferrule for the end of the same, exteriorly screw-threaded, a link supporting portion formed integrally upon the ferrule, and extended transversely of the end of the 25 fuse casing, said link supporting portion having a substantially semi-circular aperture of an area about one-half of the end of the fuse casing, a flat fuse link, arranged longitudinally within the fuse casing and 30 having its terminal portion bent over the edge of the link supporting portion of said ferrule, a metal contact plate having a flat portion and a wedge portion, the wedge portion being fitted to enter the aperture in 35 the end of the ferrule and press the fusible link sidewise against the link supporting portion of the ferrule, and a threaded end cap screwed upon the ferrule which presses the contact plate together with its wedge 40 portion against the fusible link.

5. In an inclosed electric fuse of the cartridge type, the combination of a casing, an externally screw threaded metal ferrule for the end of the same having an end wall 45 formed with an aperture having a straight side, and an adjoining flat contact surface, a metal contact plate having a boss which enters the aperture and having an adjoining flat contact surface arranged for coöperation 50 with the aforesaid contact surface for holding a fuse strip therebetween and a threaded end cap screwed onto the ferrule for applying pressure to said contact plate.

6. The combination, in an inclosed electric 55 fuse of the cartridge type of a casing, an externally screw threaded metal ferrule for the end of the same having an end wall formed with an aperture provided with a straight side, a flat fuse strip arranged longitudinally within the casing and having a terminal portion bent over the straight side of the aperture, a metal disk having a 60 wedging portion which enters the aperture and presses the fuse strip sidewise against the straight side of the aperture, and a 65

threaded end cap screwed upon the ferrule which presses the disk against the fuse strip.

7. In an inclosed electric fuse of the cartridge type, the combination of a casing, an externally screw threaded metal ferrule for 70 the end of the same having an end wall formed with an aperture having a straight side, and an adjoining flat contact surface, a fuse strip arranged longitudinally within the casing and having a terminal portion bent over the straight side of the aperture and extended over the flat contact surface, a metal disk having an engaging portion which enters the aperture and presses the fuse strip sidewise against the straight side 75 of the aperture, and having a flat contact surface for coöperation with the aforesaid contact surface and a threaded end cap screwed upon the ferrule which presses the disk against the fuse strip. 80

8. In an inclosed electric fuse of the cartridge type, the combination of a casing containing a fuse strip, an externally screw-threaded metal ferrule for the end of said casing, having an apertured end wall 85 through which a terminal portion of the fuse strip projects, a plate having a boss with an inclined side which enters the aperture and presses the fuse strip terminal portion firmly against the side of the aperture 90 to insure a good contact and an end cap screwed onto said ferrule which applies pressure to said plate and boss. 95

9. In an inclosed electric fuse of the cartridge type, the combination of a casing, a 100 threaded ferrule for the end of the same having an end wall with an aperture, said aperture having a circular side concentric with the wall of the casing and also having a straight side, a fuse strip arranged longitudinally within the casing and having a terminal portion bent over the straight side of the aperture, a metal disk having a wedging portion which enters the aperture and presses the fuse strip sidewise against 105 said straight side, and a threaded end cap screwed upon the ferrule which presses the disk against the fuse strip on the end wall of the ferrule. 110

10. In an inclosed electric fuse of the cartridge type, the combination of a casing, a threaded metal ferrule for the end of the same having an end wall provided with a semi-circular aperture, said aperture having a circular side concentric with the wall of 115 the casing and having a straight side arranged diametrically with respect thereto, a fuse strip arranged longitudinally within the casing and having a terminal portion bent over the straight side of the aperture 120 on to the end wall of the ferrule, a metal disk having an engaging portion of wedge formation which enters the aperture and presses the fuse strip sidewise against the straight side of the aperture, and a threaded 125 130

cap screwed onto the ferrule which presses the disk against the fuse strip on the end wall of the ferrule and presses its engaging portion into the aperture.

5 11. In an inclosed electric fuse of the cartridge type, the combination of a casing provided with a fixed end wall having an aperture, a fuse strip having its end portion extended through the aperture, a removable 10 plate arranged over said end wall having a boss which enters the aperture and impinges the fuse strip against the edge thereof, and a threaded end cap inclosing said plate and applying pressure thereto to hold 15 the fuse strip.

12. In an inclosed electric fuse of the cartridge type, the combination of a casing containing a fuse strip, an annular metal portion exteriorly screw-threaded and provided 20 with a fixed end wall having an aperture, and a removable plate arranged over said end wall having a boss which enters the aperture and impinges the fuse strip against the edge thereof and also against the end 25 wall, and a threaded end cap inclosing said plate and applying pressure thereto to press it into engagement with the fuse strip.

13. The combination in an inclosed fuse of the cartridge type, of a casing, a screw-threaded metal ferrule for the end of the same, having a permanent link supporting portion extending transversely of the end of the casing provided with an aperture, a

flat fuse link, arranged longitudinally within the fuse casing and having its terminal 35 portion bent over the edge of the aperture and over the link supporting portion of said ferrule, a removable metal contact member having a flat portion and a wedge portion, the wedge portion entering said aperture 40 and pressing the link sidewise against the edge thereof and the flat portion co-operating with the link supporting portion to hold the link between them, and a threaded end cap screwed to the ferrule which presses 45 the contact member against the fuse link.

14. In an inclosed fuse of the cartridge type, the combination of a casing, a ferrule for the same having a wall formed with an aperture having a straight side and an adjoining flat contact surface, a fuse strip within the casing, a metal contact member having a boss which enters the aperture and having an adjoining flat contact surface arranged for co-operation with the aforesaid 50 contact surface for holding the fuse strip therebetween and a longitudinally adjustable member for applying pressure to said contact member.

In testimony whereof, I have signed my 60 name to this specification in the presence of two subscribing witnesses.

FRANKLIN N. CONANT.
